UNITED STATES PATENT OFFICE.

JOHN R. JONES, OF SOMERVILLE, MASSACHUSETTS.

GALLEY-LOCK.

1,366,663.

Specification of Letters Patent. Patented Jan. 25, 1921.

Application filed January 21, 1920. Serial No. 352,934.

To all whom it may concern:

Be it known that I, JOHN R. JONES, an applicant to become a citizen of the United States by declaration of intention filed in 5 the superior court, Middlesex county, Mass., July 19, 1917, residing at Somerville, in the county of Middlesex and State of Massachusetts, have invented certain new and useful Improvements in Galley-Locks, of which 10 the following is a specification.

This invention relates to galley locks and has for its principal object the provision of a simple, inexpensive and durable galley lock.

15 Another object is the provision of such a galley lock which is held in place by friction, thus making it unnecessary to reconstruct or alter the galley to prepare the same for use with this invention.

20 Another object is the provision of such a galley lock which has a one-piece resilient locking means which when in locking position spreads and engages the opposite sides of the galley.

25 Referring to the drawings, wherein is illustrated a preferred embodiment of my invention:

Figure 1 is a perspective view of a galley with my improved galley lock in place.

30 Fig. 2 is a plan view of my galley lock with the double resilient locking lever in locked position.

Fig. 3 is a view similar to Fig. 2 showing the same in unlocked position.

35 Fig. 4 is an elevational cross-sectional view taken longitudinally of the lock showing the double resilient locking lever in unlocked position. This section is taken on the line 4—4 of Fig. 3.

40 Fig. 5 is a cross-sectional view on the line 5—5 of Fig. 2.

Fig. 6 is a cross-sectional view on the line 6—6 of Fig. 3.

45 Fig. 7 is a cross-sectional view on the line 7—7 of Fig. 2.

Like reference characters refer to similar parts throughout the several views.

10 designates the main body or block of the lock. 11 designates the coil of the double resilient locking lever, and 12 the lever arms.

50 Integrally a part of the arms 12 and extending in the channels 13 are the head-operating rods 14. At the end of the rods 55 14 are the friction heads 15 which engage

the galley sides 16, as shown in Fig. 2. At the outer ends of the channels 13 are enlarged conical recesses to receive the heads 15.

When in unlocked position, with the heads 15 in their recesses, the lever members 12 are 60 in the position as shown in Fig. 3. When however, it is desired to operate the lock, the lever members 12 and the coil 11 are swung down to a position as illustrated in Fig. 2.

The action of the locking member in the 65 block will now be described. Extending across the block are two slots 17 of a depth equal to that of the channel 13. The inner and adjacent sides of the channels are beveled as shown at 18 and 19 (Figs. 2, 3 and 70 4). When the double resilient locking lever is moved to locking position the lever arms 12 ride on the beveled portions 18, 19, of the channels 17 and force the heads 15 out against the sides 16.

75 In the construction of this device the channel 13 is cut from the top of the block 10, and the locking lever placed therein. Screws 20, 21 are threaded into the slot 13 and screwed into a point adjacent the rods 14 to hold the same in place. The tension in the coil 11 is such that there is always a tendency to draw in on the heads 15, the outward action being caused by the beveled portions 18, 19 when the lever is swung down to the side.

When it is desired to use this galley lock, it is only necessary to drop the lock in the galley adjacent the type, bring one side thereagainst, turn down the locking lever and 90 the type is securely held in place. To release the lock, it is only necessary to raise the locking lever, whereupon the lock may be removed.

95 It will thus be seen that I have produced a frictional galley lock which is inexpensive, easy to operate, and effective to perform its function. Since it operates by friction, no alterations are necessary in the galleys, nor is it necessary to cut notches or holes in the 100 galley to use my device.

Having described my invention what I claim is:—

1. A galley lock comprising a body portion oppositely longitudinally movable locking members within the body portion, swinging resilient lever means connected to the longitudinally movable locking members and normally tending to move the locking members into the body portion, the body 110

- portion having cams for causing the locking members to protrude when the lever means are swung to side position.
2. A galley lock comprising a body portion oppositely longitudinally movable locking members within the body portion, swinging resilient lever means connected to the longitudinally movable locking members and normally tending to move the locking members into the body portion, the body portion having cams for causing the locking members to protrude when the lever means are swung to side position, the locking members having enlarged heads for contact with the galley sides.
3. A galley lock comprising a body portion oppositely longitudinally movable locking members within the body portion, and lever members having a coil spring connecting their outer ends together and being connected at their inner ends to the locking members, whereby said locking members are yieldably held toward each other.
4. A galley lock comprising a body portion oppositely longitudinally movable locking members within the body portion, lever members connected at their inner ends to the locking members and having spring means coöperating therewith to draw said locking members together, the locking members having enlarged heads for contact with the galley sides.
5. A galley lock having a body portion, a slot therein, a one piece resilient locking means comprising a resilient coil, its ends forming lever members, the lever members being integral with oppositely extending locking members, the locking members having heads adjacent the sides of the body member, cam surfaces on the body members adjacent the lever members and in position to cause the heads of the locking members to protrude when the levers are swung to engage the cam surfaces and means for holding the locking members in the slots.
6. A galley lock having a body portion, means extending to a point adjacent one side of the body portion to engage the side of a galley and cam means for causing said means to protrude beyond the side of said body member.
7. A galley lock having a body portion, frictional means extending to points adjacent opposite sides of the body portion to engage the sides of a galley, resilient means for normally holding the frictional means retracted and means to cause the frictional means to protrude beyond the sides of the body portion.
8. A galley lock having a body portion, frictional means extending to a point adjacent one side of the body portion to engage the side of a galley, resilient means for normally holding the frictional means retracted and means including a cam to cause the frictional means to protrude beyond the side of the body portion.
9. A galley lock having a body portion, frictional members extending to points adjacent opposite sides of the body portion to engage the sides of a galley, resilient means for normally holding the frictional means retracted, movable means to cause the frictional members to protrude from the sides of the body portion, the frictional members, resilient means and movable means being formed integrally.
10. A galley lock having a body portion, means movable relative to said body portion having an enlargement for engaging one side of the galley and limiting inward movement of the member relative to said body portion, resilient means for holding said enlargement toward the body portion, and means coöperating with said body portion for forcing said member and said body portion in opposite directions toward the sides of the galley.
11. A galley lock having a body portion, a member rotatably and slidably mounted therein, resilient means for holding said member in retracted position relative to said body portion, and means coöperating with said body portion and said member for forcing them in opposite directions toward the sides of the galley.

In testimony whereof I affix my signature.
JOHN R. JONES.
